DESIGN FOR A KITCHEN FORK

Julian E. Rude, Rhinelander, Wis.

Application November 9, 1939, Serial No. 88,161

Term of patent 14 years

To all whom it may concern:

Be it known that I, Julian E. Rude, a citizen of the United States, residing at Rhinelander, in the county of Oneida and State of Wisconsin, have invented a new, original, and ornamental Design for a Kitchen Fork, of which the following is a specification, reference being had to the accompanying drawing, forming part thereof.

I claim:

The ornamental design for a kitchen fork, as shown.

JULIAN E. RUDE.
